UNITED STATES PATENT OFFICE.

SAMUEL J. QUINCY, OF SIOUX CITY, IOWA, ASSIGNOR, BY MESNE ASSIGNMENTS, TO UNION TYPEWRITER COMPANY, OF JERSEY CITY, NEW JERSEY, A CORPORATION OF NEW JERSEY.

TABULATING MECHANISM.

No. 922,812.

Specification of Letters Patent. Patented May 25, 1909.

Application filed March 3, 1903. Serial No. 145,392.

To all whom it may concern:

Be it known that I, SAMUEL J. QUINCY, a citizen of the United States, residing at Sioux City, in the county of Woodbury and State of Iowa, have invented a new and useful Improvement in Tabulating Mechanism, of which the following is a specification.

My invention relates particularly to the equipment of type-writing machines so that they shall be adapted for tabulating or similar purposes, although the invention is applicable to other key-operated machines.

My primary object is to provide improved key-operated carriage-controlling mechanism by means of which the carriage of a type-writing or similar machine may be automatically controlled in its movement from column to column or to the beginning of a new number, after a proper key has been struck.

In its simplest form, the invention comprises key-equipped mechanism for releasing a type-writer carriage from its escapement and permitting it to move under the action of its spring a predetermined distance, depending on the key struck, and then automatically connecting the carriage again, with its escapement. In machines of the type employing a movable rack meshing with a pinion connected with the escapement, the release is effected by moving the rack out of gear, and the reengagement of the pinion is automatically effected at a point which depends upon the particular key of the new mechanism which has been struck.

The accompanying drawings illustrate my improvement applied to an old machine of the Remington type, but it will be understood that the invention, in a suitable embodiment, may be applied to any type-writing machine, either as a separate attachment before or after the manufacture of the machine, or as an integral part of the machine at the time of manufacture.

In the drawings, in which like reference-characters designate like parts, in different views—Figure 1 represents a front view (partly in section) of a type-writing machine equipped with my improvements; Fig. 2, a rear view of the same; Fig. 3, a plan view of the machine; Fig. 4, a plan view of the machine with the carriage and its attachments removed; Fig. 5, a horizontal section taken as indicated at line 5 of Fig. 1; Fig.

6, a broken longitudinal section, taken as indicated at line 6 of Figs. 2 and 5; Fig. 7, a view in perspective showing a series of depresser bars employed; Fig. 8, a section taken as indicated at line 8 of Fig. 9, and showing the means employed for raising the rack of the machine out of mesh with the pinion of the escapement; Fig. 9, a broken rear view of the upper portion of the machine showing the main portion of the new mechanism; Fig. 10, a similar view with some of the parts in section and showing the position of the parts when the rack of the machine is out of engagement with its pinion; Fig. 11, a broken sectional view taken as indicated at line 11 of Fig. 4, and showing the position of the parts when the rack is in engagement with its pinion; Fig. 12, a similar section showing the position of the parts when the rack is out of engagement with its pinion; Fig. 13, a broken section taken as indicated at line 13 of Fig. 2 and showing the springs which serve to raise the depresser bars shown in Fig. 7; and Fig. 14, a sectional view taken as indicated at line 14 of Fig. 2.

A general description of the type-writing machine shown will be given for the purpose of making clear the manner in which my improvements are applied to and combined with the machine, and this will be followed by a particular description of my improvements.

A represents the frame of a typewriter of the well-known Remington type, having corner uprights or standards, A¹ rising from a base A² and supporting a top A³; A⁴, a guide, and A⁵, a guide, which serve to support the carriage in the usual manner; B, the usual ribbon and ribbon shield; C, the escapement with which the machine is provided in the usual manner and in connection with which there is employed a horizontally disposed shaft C¹ extending parallel with the sides of the machine and equipped at its front end with a pinion C²; D, a carriage moving on the guides A⁴, A⁵, and provided with a movable rack D¹ of the usual construction normally meshing with the pinion C² of the escapement; D², the usual manually operated key or lever for raising the rack D¹ out of engagement with its pinion when it is desired to permit the carriage to move freely to the left; D³, the impression roll or platen;

D¹, the carriage lifting lever; D², the roll-operating, or line-spacing, lever; D³, the removable paper table and name-plate with which the machine is equipped; E, the usual 5 notched stop-bar, bearing an adjustable stop E¹ which serves to limit the movement of the carriage under the action of its spring; F, a metal tape connecting the carriage with a spring-actuated cam F¹; G, the type-keys 10 serving to operate the type-carrying levers or type-bars G¹; H, the word-spacing bar; I, the dog rocker and escapement pawls or dogs of the escapement mechanism C which is operated in the usual manner by any of the 15 type-keys or the word-spacing key; and I¹, the usual ratchet-wheel of the escapement-mechanism which is engaged by the escapement pawls or dogs.

In the construction shown the new mechanism comprises a horizontally-disposed bar J attached to the front upright frame-members A¹, near the lower portions thereof; a key-guide J¹ supported by clips J² carried by one of the members A¹ and the bar J; a 20 series of keys K to K⁵ inclusive, operative to release the carriage from its escapement and to set a trip-device for automatically reconnecting the carriage with its escapement at predetermined points; a series of rock- 25 shafts L to L⁵ inclusive, equipped at their front ends with slotted arms L⁶ connected with the lower ends of the keys of the K series; a series of crank arms L⁷ of varying lengths connected with the rear ends of the 30 rock-shafts; a series of links M to M⁵ inclusive, connected with the cranks L⁷; a transversely-extending horizontally-disposed bar N connected with the lower portions of the 35 rear uprights A¹; a bar N¹, connected by 40 means of screws a with the bar N, a series of bearings for the rear ends of the rock-shafts being provided between the bars N and N¹; a frame-member P, rigidly connected with the frame-member N; a series of levers Q to 45 Q² inclusive, and Q³ to Q⁵ inclusive, arranged in two groups and supported on pivots b b¹ projecting from the rear surface of the member P, each of said levers having one end connected with a corresponding 50 link; a series of vertically-disposed bars, or connecting links, R to R⁵ inclusive, having their lower ends connected with the free ends of the levers of the Q series; a guide, S, for the bars of the R series, said guide 55 being connected with one of the rear uprights A¹ by means of clips c; a rack-bar-actuating lever, T, supported on a pivot d perpendicular to the rear end of the machine and carried by a bracket d¹ secured to the 60 upper surface of the top A² of the machine; an arm T¹, (Fig. 4) of said lever, extending forwardly and toward the center of the machine and provided with an upturned extremity f, bearing a roller f¹ (Figs. 11 and 65 12); a bar or rack, T², rigidly connected

with the rack-bar D¹ of the machine, and bearing upon the roller f¹; an arm T³, of the lever T provided on its upper surface with lugs or bearings g supporting a shaft g¹; a tubular latch-tripping member T⁴, surrounding the shaft or pin g¹, and provided with an upwardly-extending arm g² bearing a series of steps h to h⁵ inclusive; a guide-pin T⁵, projecting from the arm g² near its upper portion and extending parallel with the shaft g¹; a sleeve T⁶, mounted on the sleeve T⁴ and confined against longitudinal movement by lugs j with which the upper surface of the arm T⁵ is provided; an arm T⁷ connected with one end of the sleeve T⁶ 80 and provided near its extremity with a perforation working on the guide-pin T⁵; an arm T⁸ connected with the opposite end of the sleeve T⁶ and bearing at its upper end a segment T⁹ provided on one side with a 85 depressed surface k and a series of notches k¹ to k⁵ inclusive; a catch or stop T¹⁰ having a hook-like extremity l adapted to engage any one of said notches, said stop being attached firmly to the bracket d; an arm T¹¹, 90 (Figs. 4 and 8) formed integrally with the sleeve T⁶ and provided at its forward extremity with a rigidly connected pin or shaft T¹²; a rearwardly-extending arm T¹³, 95 rigidly connected with the pin or shaft T¹² and having its rear end journaled on the pin or shaft g¹; a vertical stud or guide T¹⁴, provided at its upper end with a stop m against which the pin T¹² strikes when it reaches the upper end of its traverse; a spring T¹⁵ serving normally to hold the pin T¹² in an elevated position; a latching lever or locking-member U, supported at its lower end on a pivot n projecting from the rear surface of the bar N and provided near its upper portion with a locking shoulder n¹, and at its upper extremity with a lateral projection n² which may be engaged by any one of the steps of the h series, according to the position of tripping device; a guide or keeper 100 U¹ for the upper portion of the latch U, said keeper being attached to the rear upper portion of the main frame of the machine; a scale-equipped notched trip-bar and stop-bar V supported by arms V¹ carried by the 105 carriage D; a series of trippers and stops V², connected with the bar V, and a brake X attached to a lug g of the lever T.

The bar J¹, is provided with suitable bearings or guides in which the plungers of 110 the keys of the K series move. Depending from the bar J¹ is a member p which serves to hold the lower rearwardly-turned ends of the plungers of said keys in engagement with the slots of the levers L⁶. Attached 115 to the bar J by means of screws p¹ is a bar p² between which and the bar J the front ends of the rock-shafts of the L series are journaled. The links or depresser-bars of the R series are shown in perspective in Fig. 120 125 130

7, from which it will be observed that they are provided at their lower ends with perforations for receiving the free ends of the levers of the Q series. The link R is provided simply with a forwardly-extending projection g^1 which normally is almost in contact with the upper surface of the adjacent end of the lever T as indicated by a dotted line in Fig. 9. The remaining links 10 of the R series are provided with a series of downturned ends g^1, g^2, g^3, g^4, g^5 , of successively decreasing length, thereby affording a series of steps as indicated in Fig. 6 and by dotted lines in Fig. 9. The downturned 15 arms are carried by forwardly-extending projections r with which the upper ends of the links are provided, the projections r being normally in engagement with the pin or shaft T^{12} . The member S is U-shaped as shown in Fig. 2 and has its legs s provided with slots s^1 which receive the bars of the R series. The bars are held in place by pins s^2 . The bars are normally held in position by springs s^3 , each of which 20 has one end supported by the upper leg s of the guide S and the opposite end connected with its bar. The member T^4 is normally held at one end of its guide by a spring t (Figs. 9 and 10). The lever U 25 is connected with a spring t^1 attached to the main frame of the machine.

From the detailed description of the improved mechanism given, the operation will be readily understood. The carriage of the 30 machine is operated in the usual manner through the medium of the universal bar W connected in the usual way with the dog-rocker I and actuated whenever a type-key or the word-spacing bar is operated. The 35 trippers or fingers V^2 of the improved mechanism which are also column stops, are preparatorily adjusted on the bar V, as desired, their arrangement depending upon the spaces between columns. The keys of 40 the improved mechanism are conveniently located in the rear of and above the usual keyboard, and when it is desired to move the carriage from one column to another it is only necessary to strike one of these keys. 45 The distance which the carriage will move will be determined by the key which is struck. Supposing the key K to be struck, for instance, its rock-shaft L will be turned and the lever Q actuated, thereby depressing 50 and connecting bar R and drawing down the adjacent arm of the lever T. This elevates the free end of the lever-arm T^1 , thereby raising the rack D^1 out of engagement with the pinion C^2 of the escapement mechanism. 55 This permits the carriage to move freely under the action of its spring. At the same time as when the lever T is moved, the member T^4 is turned on the axis d and this raises the shoulder or step h with which the arm 60 g^2 is equipped, into alignment with the right

end of the projection n^2 of the latch U. This likewise brings a flange or disk-sector v with which the upper end of the arm g^2 is provided into the path of the fingers or stops V^2 of the trip-bar or stop-bar. When 70 the carriage moves a sufficient distance, therefore, one of the trippers will engage the flange v and move the latch tripping member T^4 longitudinally of the shaft g^1 , whereupon the shoulder h will engage the 75 projection n^2 and trip the latch, so that the adjacent end of the lever T will fall. This allows the rack D^1 to fall and reengage the pinion C^2 of the escapement mechanism. It will of course be observed that the shoulder 80 n^1 of the latch U is drawn beneath the extremity of the arm T^3 of the lever T when said lever is actuated by depressing the bar R. When the latch U is tripped as described its left edge is forced against the 85 keeper U^1 as indicated in Fig. 4, and the carriage is then arrested by the action of the finger or stop V^2 on the finger v of the latch-tripping member T^4 and by the action of the shoulder h of this member on the latch. 90

Assuming the key K^1 to be struck, the effect is to depress the horizontally-disposed pin T^{12} a short distance, thereby rocking the member T^6 and the member T^4 upon the shaft g^1 . Further depression of the bar R causes the downturned end g^1 of said bar to bear upon the adjacent arm of the lever T and actuate the lever. This movement brings the first notch k^1 into engagement with the tooth of the stop T^{10} . Actuation of the lever 100 T raises the rack from engagement with its pinion and permits the latch U to operate, as before described, and to co-act with the segment T^9 and stop or detent T^{10} in locking the tripping member T^4 in its working 105 position. Now, however, the shoulder or step h^1 instead of the shoulder h of the longitudinally-movable latch tripping member is brought into alignment with the extremity of the projection n^2 so that when the next 110 finger or stop V^2 on the stop-bar engages said tripping-member, the member will be moved a letter space distance farther than before and the latch will be tripped, the carriage will be arrested, and the rack will fall 115 and reengage with the escapement pinion. Assuming the key K^2 to be struck, the first action is to depress the pin or shaft T^{12} a sufficient distance to bring the second notch k^2 of the projection n^2 into alignment with the tooth of the stop T^{10} , and to bring the shoulder or step h^2 of the latch-tripping member into a position a little below and a little more than two letter space distances from the right end of the projection n^2 of the latch. Then the shorter 120 downturned end g^2 of the bar R^2 engages the upper surface of the adjacent arm of the lever T and further depression of the bar actuates the said lever, permitting the latch to act, elevating the rack out of engagement 125 130

with its pinion, and bringing the shoulder h^2 to the same height as the extremity of the projection n^2 . When a trip-finger or stop V^2 actuates the latch tripping member again, therefore, said member is moved a greater distance than before, prior to the tripping of the latch, the arrest of the carriage, and the reengagement of the rack with the pinion of the escapement mechanism. As the successive keys are operated to and including the key K^3 , the successively decreasing lengths of the downturned ends of the lever-depressing bars permit the shaft or pin T^{12} to be depressed correspondingly greater distances, before the lever T is actuated, and by this means provision is made for properly setting the latch tripping member and its guide so as to cause the latch to be tripped and the carriage arrested and restored to the control of the escapement after successively increasing traverses of the carriage.

The faces of the steps or shoulders h , h^1 etc. of the latch-tripping member are in parallel planes at letter-space distances apart and from the foregoing description it is plain that this latch-tripping member is also a denominational stop-device, which co-acts with the column-stops V^2 and the latch U in arresting the carriage at different denominational positions and at different columnar positions, and that with this stop-device is combined means to lock it in its working position when pressure is removed from the actuated denominational key, any of the keys K , K^1 , K^2 , K^3 , K^4 or K^5 being a denominational key, or a tabulating key, and that each of the column-stops V^2 , which are movable by the carriage into contact with the key-actuated stop-device is adjustable on the stop-bar to positions at letter-space distances apart.

It will be understood, of course, that the mechanism is adapted for use in tabulating one or any desired number of columns of numbers. The carriage, assuming it to be at the right of a column, will move to the proper position to bring the first figure of the number to be printed in its proper order, regardless of whether the first figure is of the units, tens or any other order. It will be understood that the number of keys and corresponding parts may be increased as desired to permit numbers of any desired magnitude to be written. The number of trip-finger or column-stops employed on the combined trip-bar and stop-bar will, of course, depend upon the number of columns which it is desired to make, and the number of steps or shoulders on the latch-tripping member will depend upon the magnitude of the largest number to be written.

A brake may be employed or not, as required. The brake X shown (Fig. 14) is adapted to frictionally engage the under-

side of the trip-bar of the carriage when the lever T is raised.

It will be understood that the embodiment of the invention may be variously modified, according to the requirements of the particular machine to which it is applied; also it will be understood that the arrangement of the parts of the mechanism is likely to differ when designed for application to a machine at the time of the manufacture of the machine, instead of as a distinct attachment to an old machine. Moreover, when designed as a distinct attachment to an old machine, the form, number and arrangement of the parts are capable of wide variation. The carriage-releasing lever, or member, may act upon any desired portion of the escapement-mechanism to free the carriage. In a machine having a shiftable ratchet-bar, for instance, this member may be moved by the carriage-releasing member; and in some machines it may be desirable to have the carriage-releasing member act directly upon the pawl of the escapement-mechanism.

Any suitable latch, or pawl, may be employed in the trip-mechanism for holding the carriage free, or keeping it disconnected, and the disconnection may occur at any portion of the escapement mechanism, the primary object being to render it unnecessary to hold a key while the carriage is passing to the proper position to receive a number or word.

Changes in the details of the invention and arrangement of parts thereof are contemplated, hence no undue limitation should be understood from the foregoing detailed description which has been given for the purpose of fully and clearly explaining the invention.

What I claim as new and desire to secure by Letters Patent, is:—

1. In a typewriting machine, the combination with a power-driven carriage, and an escapement, of means including a key to release the carriage from the control of the escapement, means to keep the carriage thus released after pressure is removed from the key, and stops to arrest the carriage at a position regulated by the arrangement of said stops, one of said stops being movable by a key to its working position before the carriage is released, and the other being movable by the carriage into contact with the key-actuated stop.

2. In a typewriting machine, the combination with a power-driven carriage, and an escapement, of means including a key to release the carriage from the control of the escapement, means to keep the carriage thus released after pressure is removed from the key, and stops to arrest the carriage at a position regulated by the arrangement of said stops, one of said stops being adjust-

able to positions at letter-space distances apart.

3. In a typewriting machine, the combination with a power-driven carriage, and an escapement, of means including a key to release the carriage from the control of the escapement, a stop movable to its working position by said key, means to keep the carriage thus released and said stop in its working position after pressure is removed from the key, and a stop movable by the carriage into contact with the first-mentioned stop and coöperative with the first-mentioned stop to arrest the carriage at a position regulated by the arrangement of said stops.

4. In a typewriting machine, the combination with a power-driven carriage, and an escapement, of means including a key to release the carriage from the control of the escapement, a stop movable to its working position by said key, means to keep the carriage thus released and said stop in its working position after pressure is removed from the key, and a stop coöperative with the first-mentioned stop to arrest the carriage at a position regulated by the arrangement of said stops, one of said stops being adjustable to positions at letter-space distances apart.

5. In a typewriting machine, the combination with a power-driven carriage, and an escapement, of means including a key to release the carriage from the control of the escapement, means to keep the carriage thus released after pressure is removed from the key, and stops to arrest the carriage at a position regulated by the arrangement of said stops, one of said stops being movable by a key to its working position before the carriage is released, and the other being movable by the carriage into contact with the key-actuated stop, and said combination including means automatically operative to restore the carriage to the control of the escapement after the carriage is arrested.

6. In a typewriting machine, the combination with a power-driven carriage, and an escapement, of means including a key to release the carriage from the control of the escapement, means to keep the carriage thus released after pressure is removed from the key, and stops to arrest the carriage at a position regulated by the arrangement of said stops, one of said stops being adjustable to positions at letter-space distances apart, and said combination including means automatically operative to restore the carriage to the control of the escapement after the carriage is arrested.

60 7. In a typewriting machine, the combination with a power-driven carriage, and an escapement, of means including a key to release the carriage from the control of the escapement, a stop movable to its working position by said key, means to keep the car-

riage thus released and said stop in its working position after pressure is removed from the key, and a stop movable by the carriage into contact with the first-mentioned stop and coöperative with the first-mentioned stop to arrest the carriage at a position regulated by the arrangement of said stops, and said combination including means automatically operative to restore the carriage to the control of the escapement and the key-actuated stop to its normal position after the carriage is arrested.

8. In a typewriting machine, the combination with a power-driven carriage, and an escapement, of means including a key to release the carriage from the control of the escapement, a stop movable to its working position by said key, means to keep the carriage thus released and said stop in its working position after pressure is removed from the key, and a stop coöperative with the first-mentioned stop to arrest the carriage at a position regulated by the arrangement of said stops, one of said stops being adjustable to positions at letter-space distances apart, and said combination including means automatically operative to restore the carriage to the control of the escapement and the key-actuated stop to its normal position after the carriage is arrested.

9. In a typewriting machine, the combination with a power-driven carriage, and an escapement, of means including a key to release the carriage from the control of the escapement, and mechanism automatically operative when pressure is removed from the key to keep the carriage thus released, and then to arrest it, and then to restore it to the control of the escapement, said mechanism including an adjustable stop and being effective to arrest the carriage at any desired position to be determined by an adjustment of said stop.

10. In a typewriting machine, the combination with a power-driven carriage, and an escapement, of means including a key to release the carriage from the control of the escapement, and mechanism automatically operative when pressure is removed from the key to keep the carriage thus released, and then to arrest it and then to restore it to the control of the escapement, said mechanism including a stop mounted on the carriage and adjustable to positions at letter-space distances apart, and said mechanism being effective to arrest the carriage at any desired position to be determined by an adjustment of said stop.

11. In a typewriting machine, the combination with the paper-carriage, of a tabulating stop movable by a key to its working position, means to lock said stop in its working position when pressure is removed from the key, and means coöperative with said stop to arrest the carriage, the last-men-

- tioned means including another stop movable by the carriage into contact with the first-mentioned stop.
12. In a typewriting machine, the combination with the paper-carriage, of a tabulating stop movable by a key to its working position, means to lock said stop in its working position when pressure is removed from the key, and means including another stop coöperative with the first-mentioned stop to arrest the carriage, one of said stops being adjustable to positions at letter-space distances apart.
13. In a typewriting machine, the combination with the paper-carriage, of a stop-device having a series of denominational stop-holders, said device being movable by key-actuated means to its different working positions, means to lock said stop-device in its working position when pressure is removed from said key-actuated means, and means including another stop coöperative with said stop-device to arrest the carriage.
14. In a typewriting machine, the combination with the paper-carriage, of an angularly movable stop-device having a series of denominational stop-shoulders, key-actuated means operative to turn said device to its different working positions, means to lock said stop-device in its working position when pressure is removed from said key-actuated means, and means including another stop coöperative with said stop-device to arrest the carriage.
15. In a typewriting machine, the combination with the paper-carriage, of an angularly movable stop-device having a series of denominational stop-shoulders, a set of denominational keys operative to turn said device to its different working positions, means to lock said stop-device in its working position when pressure is removed from the actuated denominational key, and means including another stop coöperative with said stop-device to arrest the carriage.
16. In a typewriting machine, the combination with the paper-carriage, of an angularly movable stop-device having a series of denominational stop-shoulders, said device being arranged to turn on two axes contained in vertical planes parallel and at right angles respectively to the axis of the platen, key-actuated means operative to turn said device to its different working positions, means to lock said stop-device in its working position when pressure is removed from said key-actuated means, and means including another stop coöperative with said stop-device to arrest the carriage.
17. In a typewriting machine, the combination with the paper-carriage, of an angularly movable stop-device having a series of denominational stop-shoulders, said device being arranged to turn on two axes contained in vertical planes parallel and at right angles respectively to the axis of the platen, a set of denominational keys operative to turn said device to its different working positions, means to lock said stop-device, in its working position when pressure is removed from the actuated denominational key, and means including another stop coöperative with said stop-device to arrest the carriage.
18. In a typewriting machine, the combination with the paper-carriage, of a tabulating stop movable by a key to its working position, means including a latch to lock said stop in its working position when pressure is removed from the key, and means including another stop coöperative with the first-mentioned stop and with said latch to arrest the carriage.
19. In a typewriting machine, the combination with the paper-carriage, of an angularly movable stop-device having a series of denominational stop-shoulders, key-actuated means operative to turn said device to its different working positions, means including a latch to lock said stop-device in its working position when pressure is removed from the key, and means including another stop coöperative with said stop-device and with said latch to arrest the carriage.
20. In a typewriting machine, the combination with the paper-carriage, of an angularly movable stop-device having a series of denominational stop-shoulders, a set of denominational keys operative to turn said device to its different working positions, means including a latch to lock said stop-device in its working position when pressure is removed from the actuated denominational key, and means including another stop coöperative with said stop-device and with said latch to arrest the carriage.
21. In a typewriting machine, the combination with a power-driven carriage, and an escapement, of a tabulating stop, a key operative to move said stop to its working position and to release the carriage from the control of the escapement, means to lock said stop in its working position, the action of said means being independent of said key after the carriage is released, and means coöperative with said stop to arrest the carriage, the last-mentioned means including another stop movable by the carriage into contact with the first-mentioned stop.
22. In a typewriting machine, the combination with a power-driven carriage, and an escapement, of a tabulating stop, a key operative to move said stop to its working position and to release the carriage from the control of the escapement, means to lock said stop in its working position, the action of said means being independent of said key after the carriage is released, and means including another stop coöperative with the first-mentioned stop to arrest the carriage,

- one of said stops being adjustable to positions at letter space distances apart.
23. In a typewriting machine, the combination with a power-driven carriage, and an escapement, of a stop-device having a series of denominational stop-shoulders, key-actuated means operative to move said stop-device to its different working positions and to release the carriage from the control of the escapement, means to lock said stop-device in its working positions, the action of the locking means being independent of a key after the carriage is released, and means including another stop coöperative with said stop-device to arrest the carriage. 70
24. In a typewriting machine, the combination with a power-driven carriage, and an escapement, of an angularly movable stop-device having a series of denominational stop-shoulders, key-actuated means operative to turn said stop-device to its different working positions and to release the carriage from the control of the escapement, means to lock said stop-device in its working positions, the action of the locking means being independent of a key after the carriage is released, and means including another stop coöperative with said stop-device to arrest the carriage. 75
25. In a typewriting machine, the combination with a power-driven carriage, and an escapement, of an angularly movable stop-device having a series of denominational stop-shoulders, a set of denominational keys operative to turn said stop-device to its different working positions and to release the carriage from the control of the escapement, means to lock said stop-device in its working positions, the action of the locking means being independent of the actuated denominational key after the carriage is released, and means including another stop coöperative with said stop-device to arrest the carriage. 80
26. In a typewriting machine, the combination with a power-driven carriage, and an escapement, of an angularly movable stop-device having a series of denominational stop-shoulders, said device being arranged to turn on two axes contained in vertical planes parallel and at right angles respectively to the axis of the platen, key actuated means operative to turn said stop-device to its different working positions and to release the carriage from the control of the escapement, means to lock said stop-device in its working positions, the action of the locking means being independent of a key after the carriage is released, and means including another stop coöperative with said stop-device to arrest the carriage. 85
27. In a typewriting machine, the combination with a power-driven carriage, and an escapement, of a tabulating stop, a key operative to move said stop to its working position and to release the carriage from the control of the escapement, means including a latch to lock said stop in its working position, the action of said latch being independent of the key after the carriage is released, and means including another stop coöperative with the first mentioned stop 90 and with said latch to arrest the carriage. 95
28. In a typewriting machine, the combination with a power-driven carriage, and an escapement, of an angularly movable stop-device having a series of denominational stop-shoulders, key-actuated means operative to turn said stop-device to its different working positions and to release the carriage from the control of the escapement, means including a latch to lock said stop-device in 100 its working positions, the action of said latch being independent of the key after the carriage is released, and means including another stop coöperative with said stop-device and with said latch to arrest the carriage. 105
29. In a typewriting machine, the combination with a power-driven carriage, and an escapement, of an angularly movable stop-device having a series of denominational stop-shoulders, a set of denominational keys operative to turn said stop-device to its different working positions and to release the carriage from the control of the escapement, means including a latch to lock said stop-device in 110 its working positions, the action of said latch being independent of the actuated denominational key after the carriage is released, and means including another stop coöperative with said stop-device and with said latch to arrest the carriage. 115
30. In a typewriting machine, the combination with a power-driven carriage, and an escapement, of an angularly movable stop-device having a series of denominational stop-shoulders, a set of denominational keys operative to turn said stop-device to its different working positions and to release the carriage from the control of the escapement, means including a latch to lock said stop-device in 120 its working positions, the action of the latch being independent of the actuated denominational key after the carriage is released, and means including another stop coöperative with said stop-device and with said latch to arrest the carriage. 125
31. In a typewriting and tabulating mechanism, the combination of a power driven carriage, escapement devices therefor, a column stop, a coöperating stop, a carriage releasing device, means for mechanically detaining said carriage releasing device in abnormal position, and means for automatically freeing said carriage releasing device from the control of its detaining means when the carriage is arrested. 130

32. A typewriter having key controlled devices for taking the paper carriage from the control of its step by step feeding devices and putting it in the control of a variable spacing device, and a lock for locking the parts in this position free from interference from the spacing key and all type keys until the movement of the carriage is completed whereby a variable movement of the carriage is secured from an instantaneous movement of the controlling key. 70
33. A typewriter having key controlled devices for taking the paper carriage from the control of the step by step feeding devices and putting it in the control of a variable spacing device, a lock for locking the parts in this position, free from interference of the spacing key and all type keys, and devices for automatically removing the lock as 75 the carriage is arrested. 80
34. A typewriter having key controlled devices for taking the paper carriage from the control of the step by step feeding devices and putting it in the control of a variable spacing device, a lock for locking the parts out of control of the spacing key and all type keys, and devices for automatically restoring the carriage to the control of the step by step feeding devices. 85
35. In a typewriting and tabulating mechanism, the combination of a power driven carriage, escapement mechanism therefor, a carriage releasing lever, a column stop, a co-operating stop, means for projecting one of 90 said stops and simultaneously operating the carriage releasing lever, means for locking the carriage releasing lever against interference from the spacing key and all type keys during a variable feed movement, the said construction including provisions whereby the projected stop and its actuating means remain at rest until the unlocking of the carriage releasing lever. 95
36. In a typewriting and tabulating mechanism, the combination of a power driven carriage, letter feeding devices therefor, a column stop, a co-operating stop, a key for projecting one of said stops, a carriage releasing device operated by said key, and a lock for holding said carriage releasing device in abnormal position against interference from the spacing key and all type keys. 100
37. In a typewriting and tabulating mechanism, the combination of a power driven carriage, letter feeding devices therefor, a column stop, a co-operating stop, a key for projecting one of said stops, a carriage releasing device operated by said key, and a lock also operated by said key for holding 105 said carriage releasing device in abnormal position free from interference from the spacing key and all of the type keys. 110
38. In a device of the class described, the combination of a frame, a carriage slidably mounted on said frame and normally urged 115 toward one end of same; a suitable feeding device for controlling the movement of said carriage along said frame, a stop on said carriage, a detent mounted on said frame and movable into and out of the path of said stop, and adapted to engage said stop for the purpose of stopping the carriage, said detent being also movable with said carriage after having been engaged by said stop, a key adapted to move said detent into position for engaging said stop, and means for simultaneously releasing said carriage. 120
39. In a device of the class described, the combination of a frame; a carriage slidably mounted on said frame and normally urged toward one end of same, a suitable feeding device for controlling the movement of said carriage along said frame, a stop on said carriage, a detent mounted on said frame and movable into and out of the path of said stop, and adapted to engage said stop for the purpose of stopping the carriage, said detent being also movable with said carriage after having been engaged by said stop, a spring adapted to yieldingly resist the movement of said detent with said carriage, a key adapted to move said detent into position for engaging said stop, and simultaneously release said carriage, and means for limiting the yielding of said detent. 125
40. In a device of the class described, the combination of a frame, a carriage slidably mounted on said frame and normally urged toward one end of same, a suitable feeding device for controlling the movement of said carriage along said frame, a stop on said carriage, a detent mounted on said frame and movable into and out of the path of said stop, and adapted to engage said stop for the purpose of stopping the carriage, said detent being also movable with said carriage after having been engaged by said stop; and a plurality of keys each adapted to move said detent into position for engaging said stop and each adapted to limit to a different degree the movement of said detent along the path of said stop. 130
41. In a device of the class described, the combination of a frame, a carriage slidably mounted on said frame and normally urged toward one end of same, a suitable feeding device for controlling the movement of said carriage along said frame, a stop on said carriage, a detent mounted on said frame and movable into and out of the path of said stop, and adapted to engage said stop for the purpose of stopping the carriage, said detent being also movable with said carriage after having been engaged by said stop, yielding means for resisting the movement of said detent with said carriage; a plurality of keys each adapted to move said detent into position for engaging said stop and each adapted to permit said detent to yield to a different degree. 135

42. In a typewriting machine, the combination with a power driven carriage and an escapement, of key-actuated means, separate from the escapement, for releasing the carriage from the control of the escapement, means to keep the carriage from control of the escapement, and a carriage-actuated trip to force the last mentioned means out of action.
43. In mechanism of the character described, the combination of trip-mechanism for freeing the carriage of the machine from its escapement, and a carriage-carried trip-bar equipped with a plurality of fingers for forcing said trip-mechanism out of action.
44. In mechanism of the character described, the combination of trip-mechanism for freeing the carriage from its escapement, and a trip-bar carried by the carriage and provided with an adjustable finger operative upon said trip-mechanism to automatically re-connect the carriage with the escapement.
45. In mechanism of the character described, the combination of a lever operative to free the carriage from its escapement, a latch to hold the lever in its working position, and a carriage-actuated trip-finger to trip said latch.
46. In mechanism of the character described, the combination of a suitably-actuated lever for freeing the carriage from its escapement, a latch serving to lock said lever in its working position, and means carried by the carriage for tripping said latch.
47. In mechanism of the character described, means for freeing the carriage from its escapement, a locking device operative on said means, a movable device serving to force said locking device out of action, and means operative on said movable device to cause it to act on the locking device.
48. In mechanism of the character described, the combination with a key of means for freeing the carriage from its escapement and automatically restoring the connection including a movable member provided with a series of shoulders, and carriage-actuated means for moving said member.
49. In mechanism of the character described, the combination of a member serving to free the carriage from the escapement, a yielding member movably connected with said first-named member, and means carried by the carriage for moving said yielding member.
50. In mechanism of the character described, the combination of a carriage-releasing member, a latch therefor, a tripping member for said latch movably connected with the carriage-releasing member, and carriage-actuated means for moving said latch tripping member.
51. In mechanism of the character de-
scribed, the combination of a carriage-
releasing member, a locking member there-
for, a movable member operative on said
locking member, means for preparately
setting said movable member and then mov-
ing the carriage-releasing member, and car-
riage-actuated means operative on said mov-
able member.
52. In mechanism of the character de-
scribed, the combination of a carriage-
releasing lever, a latch therefor, a latch-
tripping member carried by said lever, and
means for preparately setting said latch-
tripping member and actuating said car-
riage-releasing member, for the purpose set
forth.
53. In mechanism of the character de-
scribed, a carriage-releasing lever, a latch
therefor, a latch-tripping member provided
with a series of shoulders and mounted on
said lever, and means for preparately set-
ting said latch-tripping member and actuat-
ing said carriage-releasing lever.
54. In mechanism of the character de-
scribed, the combination of a carriage-
releasing lever, a latch therefor, a latch-trip-
ping member pivotally mounted on said lever
and capable of movement longitudinally of
its pivot, and means for rotating said latch-
tripping member and actuating said car-
riage-releasing lever, for the purpose set
forth.
55. In mechanism of the character de-
scribed, the combination of a carriage-
releasing member, a latch therefor, a latch-
tripping member movably mounted on said
first-named member, and a key-actuated
member provided with means for prepara-
tory setting said latch-tripping member
and then actuating said carriage-releasing
member, for the purpose set forth.
56. In mechanism of the character de-
scribed, the combination of a suitably ful-
crumed carriage-releasing lever, a latch
therefor, a pivoted longitudinally-movable
latch-tripping member carried by said lever,
a key-operated member provided with two
shoulders, one of which preparately moves
said latch-tripping member and the other
of which then actuates said carriage-releas-
ing lever, and means carried by the carriage
for actuating said latch-tripping member.
57. In mechanism of the character de-
scribed, the combination of a carriage-re-
leasing member, a suitable latch therefor, a
latch-tripping member pivotally and longi-
tudinally movable on said carriage-releasing
member and provided with a plurality of
shoulders, each of which may be made to act
on said latch, means for preparately ro-
tating said latch-releasing member and then
moving said carriage-releasing member to
effect a release of the carriage and bring one
of said shoulders into alignment with a part

of the latch, and means carried by the carriage for moving said latch-releasing member into contact with the latch.

58. In mechanism of the character described, the combination of a suitably-fulcrumed carriage-releasing lever, a suitable latch therefor, a latch-tripping member pivotally supported on said lever and movable longitudinally of its pivot, an arm 10 through the medium of which said latch-tripping member is rotated, a key-actuated member provided with means for moving said arm to preparatorily set said latch-tripping member and then to actuate said lever, and carriage-actuating means for moving said latch-tripping member to automatically re-connect the carriage with the escapement.

59. In mechanism of the character described, the combination of a lever provided 20 with a rack-actuating arm, a latch for said lever, and means for tripping said latch.

60. In mechanism of the character described, the combination of a lever provided 25 with a rack-moving-and-sustaining arm and a latch-engaging arm, a latch for said lever, a latch-tripping member carried by said lever, and carriage-actuated means for moving said latch-tripping member.

61. The combination with a type-writing 30 machine carriage equipped with a movable rack engaging a pinion of the escapement mechanism, of a bar secured to said rack, a lever provided with an arm serving to elevate said rack through the medium of said 35 bar, a latch for said lever, and means for tripping said latch, for the purpose set forth.

62. In mechanism of the character described, the combination of a carriage-releasing lever, a latch therefor, a yieldingly 40 held latch-tripping member provided with a plurality of shoulders, means for bringing any desired shoulder of said last-named member into alinement with the latch and locking said member against rotation, and 45 means carried by the carriage for moving said latch-tripping member against the latch.

63. In mechanism of the character described, the combination of a carriage-releasing lever, a suitable latch, and latch-tripping means comprising a member movable toward the latch, a guide for said member equipped with a toothed segment, and a stationary tooth serving to lock said segment, for the purpose set forth.

64. In mechanism of the character described, the combination of a carriage-releasing member, a latch therefor, a latch-tripping member pivoted on said first-named member and capable of movement longitudinally of its pivot, a sleeve on the pivot of said latch-tripping member equipped with a toothed segment and a guide for the latch-tripping member, a catch 65 for engaging said segment, and means for

rotating the latch-tripping member and its guide and then actuating said carriage-releasing member, for the purpose set forth.

65. In mechanism of the character described, the combination of a carriage-releasing member, a latch therefor, latch-tripping means, including a member carried by the carriage, and a key-actuated rock-shaft connected with and serving to actuate said carriage-releasing member.

66. In mechanism of the character described, the combination of a carriage-releasing member, a latch therefor, a latch-tripping member, a plurality of keys, and a connection between each of the several keys 80 and the latch-tripping member and the carriage-releasing member, the connection with the carriage-releasing member being loose to permit the latch-tripping member to be preparatorily set, for the purpose set forth. 85

67. In mechanism of the character described, the combination of a carriage-releasing lever, a latch therefor, a latch-tripping member pivotally supported on said lever and operated through a projecting stem, and a plurality of key-actuated members provided with loops for engaging said stem and with shoulders for engaging said lever, said shoulders being arranged in steps, 90 for the purpose set forth.

68. In mechanism of the character described, the combination of a carriage-releasing lever, a suitable latch, a latch-tripping member provided with a plurality of shoulders arranged in steps, said last-named member being pivotally supported on said lever, a stem through the medium of which said latch-tripping member is rotated, a plurality of key-actuated members provided with means for moving said stem and having shoulders arranged in steps corresponding with the steps of said latch-tripping member, and means carried by a carriage for moving said latch-tripping member.

69. In mechanism of the character described, a suitably fulcrumed lever, a latch-tripping member pivotally supported thereon and provided with a plurality of steps, a pivotally-supported guide for said last-named member equipped with a toothed segment, and means for engaging the teeth of said segment.

70. In mechanism of the character described, the combination of a latch-controlled carriage-releasing member, and a carriage-carried trip-bar equipped with a plurality of adjustable trip-fingers, for the purpose set forth.

71. In mechanism of the character described, the combination of a carriage-releasing member, a key-controlled member serving to actuate the same, a latch for said first-named member, a latch-tripping member movably supported on said first-named member, and a plurality of key-controlled 125 130

members having connections with said latch-tripping member, for the purpose set forth.

72. In mechanism of the character described, the combination of a carriage-releasing lever, a latch therefor, a latch-tripping member pivotally supported on said lever and capable of movement longitudinally of its pivot, a stop limiting the rotation of said member in one direction, a spring for holding said member in its normal position of rest, means for rotating said latch-tripping member against the action of said spring and actuating said carriage-releasing lever, and means carried by the carriage for striking said latch-tripping member.

73. In mechanism of the character described, the combination of a carriage-releasing member, a latch therefor, a latch-tripping member movably connected with said lever, a plurality of levers connected with said latch-tripping member and said carriage-releasing lever, keys connected with and serving to actuate said plurality of levers, and a carriage-carried trip-bar provided with a plurality of trip-fingers, for the purpose set forth.

74. In mechanism of the character described, the combination of a latch-controlled carriage-releasing member, a latch-tripping member movably mounted thereon, a finger-equipped trip-bar carried by the carriage of the machine, and a plurality of vertically

moving members having loose connections with said carriage-releasing member and closer connections with said latch-tripping member, for the purpose set forth.

75. In mechanism of the character described, the combination of a carriage-releasing lever, a latch therefor, a latch-tripping member provided on one side with a plurality of steps for engaging said latch, a guide pivotally supported on said first-named lever and equipped with a toothed segment, a stationary stop provided with a tooth opposed to the teeth of said segment, whereby in the elevation of said first-named lever the teeth of said segment are brought into engagement with the tooth of said stop, and means for rotating said segment and then actuating said carriage-releasing lever, for the purpose set forth.

76. In mechanism of the character described, the combination with the carriage and escapement of the machine, of trip-mechanism for maintaining the carriage disconnected from the escapement and automatically restoring the connection, including a carriage-carried tripper, and a brake connected with said trip-mechanism, for the purpose set forth.

SAMUEL J. QUINCY.

In the presence of—

J. A. JOHNSON,

A. L. FREIBOURG.
